UNITED STATES PATENT OFFICE

ALEXANDER BOYNTON, OF SAN ANTONIO, TEXAS

DEVICE FOR CEMENTING WELLS.

Application filed December 4, 1925. Serial No. 73,189.

This invention relates to a device for cementing wells and is of the type disclosed in my co-pending applications for methods of and devices for cementing wells filed October 1, 1925, Serial No. 59,887 and filed October 1, 1925, Serial No. 59,888.

The object of the present invention is to provide a novel form of device adapted for use in carrying out the method set out in the 10 co-pending applications referred to and which makes provision for the escape of gas in the cementation of one-string wells. This feature has the advantage of avoiding agitation of the cement. It is well known that cement which is agitated while still in a liquid or semi-liquid state will not set. This advantage is had in the present case without losing the advantage of the back pressure valve.

20 A further object resides in the provision of a novel form of combined back pressure valve and seat for the combined signal ball and valve which is so organized with the casting as to be held against spinning when the 25 cement and the seat and back pressure valve are being drilled out after the cement is set. The present invention also provides means for preventing any of the connections from backing off when the cementing device is being drilled out.

Other objects and advantages reside in certain novel features of the construction, arrangement and combination of parts which will be hereinafter more fully described and 35 particularly pointed out in the appended claims, reference being had to the accompanying drawings forming a part of this specification, and in which:—

Figure 1 is a view partly in vertical section and partly in elevation, showing a portion of a device adapted for use in cementing one-string wells,

Figure 2 is a similar view of a form of the invention adapted for use in cementing two-string wells, and

Figure 3 is a view in horizontal section on the line 3—3 of Figure 1.

Referring to the drawings it will be seen that in both forms of the invention there is provided a cylindrical body portion 1 which is incorporated in the string of tubing or casing and which has diametrically opposite cement discharge openings 2 controlled by a rubber sleeve valve 3 held in position by retaining cups 4 and having discharge open-

ings 5 staggered with respect to the openings 2 (see Fig. 3).

A coupling member 6 is screwed onto the upper end of the body 1 and serves to connect the body with the next uppermost section of the string of well casing (not shown). Hollow headed set screws 6^a are engaged with the coupling member and body portion to prevent the coupling member from backing off when the cementing device is being drilled out. A combined signal and differential float valve seat, designated generally at 7, is provided and has a flange 8 threadedly connected with internal threads on the coupling member 6 and locked in position by locking screws or hollow headed set screws 9. The locking screws 9 prevent spinning of the parts 7 when the same are being drilled out after the cement is set. The flange 8 not only provides a mounting means for the partition 7 but also provides a valve seat for a back pressure valve 10. In the form of the invention shown in Figure 2 the valve 10 has its edge beveled off, as at 11, and the flange 8 is similarly beveled off, as at 12. In other respects back pressure valves are the same in both embodiments. Each back pressure valve 10 is mounted for sliding movement on a guide stud 13 fixedly secured on a cross bar 14 carried by the partition 7. A spring 15 abuts the underside of the back pressure valve 10 and also a collar 16 is provided on the lower end of the stud 13. This is the ordinary back pressure valve widely used in oil well practice. The part 7 not only includes the flange 8 but also a substantially double cone-shaped shell or member 16, the upper cone 17 of which provides a seat for the combined differential float valve and signal ball 18. As disclosed in my co-pending application this combined differential float valve and signal ball includes a ball member 18^a and a handle member 18^b, the handle member 18^b being cut off to give the combined differential float valve and signal ball 18 the proper specific gravity so that it will float in the cement and sink in the mud fluid.

In cementing one-string wells a barrier plate 20 is threadedly connected with the coupling 21 threadedly connected to the lower end of the body 1 and the barrier plate is locked in position by means of hollow headed lock screws 22 which are identical with the lock screws 9. The coupling 21 is also prevented from backing off when the

cementing device is being drilled out by virtue of the provision of the hollow headed set screws or lock screws 21^a.

In order to provide for the outlet of any gas, oil or water under pressure that may be encountered without permitting the gas to disturb the liquid cement on outside of the casing, an outlet tube 23 is provided and extends down through an opening 24 10 provided therefor in the plate 20. The lower end of the opening 24 is flared and the lower end of the tube 23 is swedged or displaced outwardly, as at 23^a, against the flared lower end of opening 24. The upper 15 end of the tube 23 is connected with the lower end of the stud 13 and the stud is formed with a lengthwise passage or opening which opens out to above the back pressure valve. A ball valve 26 is provided and 20 co-acts with a seat 27 provided around the passage 25 at the upper end thereof. This ball valve 26 is welded or otherwise suitably secured to a valve rod 28 which extends down through the tube 23 and has an angularly bent end 29 to limit its upward displacement. The ball valve 26 prevents the cement from flowing down through the tube but permits the escape of gas. By thus providing for the escape of gas agitation of the 25 liquid cement is prevented and the same is given an opportunity to properly set.

In the form of the invention shown in Figure 2, the barrier plate 20 is omitted and a set shoe 35 locked in position by hollow

headed set screws 36 replaces the coupling 35 member 21. The outlet tube 28 is also omitted but the outlet passage 25 remains in the stud 13 and as before has a valve seat 27 at its upper end with which the ball valve 26 co-acts. The ball valve also has a valve 40 rod 28^a secured thereto. The valve rod 28^a is shorter than the valve rod 28 and terminates below the stud 13 in an outturned end 29^a.

I claim:

1. A device for cementing wells including a combined back pressure valve seat and seat for a differential float and valve comprising a flange, and a double conical member connected with the flange. 45

2. A device for cementing wells including a tubular member having its opposite ends flared, one of the flared ends providing a seat for a differential float and valve, the other flared end having a peripheral flange, and a back pressure valve adapted to engage the flange. 50

3. A device for cementing wells including a tubular member having its opposite ends flared one of the flared ends providing a seat for a differential float and valve, the other 55 flared end having a peripheral flange, a back pressure valve adapted to engage the flange, said back pressure valve being provided with an opening, a tubular member slidably mounted in said opening, a valve at one end of the tubular member and adjacent the differential float and valve. 60
